UNITED STATES PATENT OFFICE.

GEORGE W. SAVAGE, OF CHESTER, PENNSYLVANIA.

FITTING FOR SYSTEMS UTILIZING HIGH PRESSURE.

1,174,356.

Specification of Letters Patent.

Patented Mar. 7, 1916.

Application filed June 22, 1914. Serial No. 846,556.

To all whom it may concern:

Be it known that I, GEORGE W. SAVAGE, a citizen of the United States, residing at Chester, in the county of Delaware and 5 State of Pennsylvania, have invented a certain new and useful Fitting for Systems Utilizing High Pressure, of which the following is a specification.

The invention, generally stated, has relation to a fitting employed in systems utilizing high pressure, as for instance, gas, air, steam and like systems and has more particular relation to the providing of a fitting for use in connection with high pressure gas 15 systems used for illuminating purposes in residences, business houses and the like.

The principal object of the present invention is to provide a fitting embracing few parts, which may be economically manufactured, readily assembled, positioned and set for efficient use without further regulation and which parts when so positioned shall be interlocked and sealed so that tampering with the valve and valve rod thereof by unauthorized persons cannot readily be accomplished or which in any event cannot be accomplished without the fact of such tampering being brought to the attention of an authorized agent inspecting the system to 30 which the fitting is attached, thereby providing maximum safety for the user.

A further object of the invention is to provide a fitting of the above type in which the valve thereof when once positioned (except for cleaning, repairing or the like purposes) does not require regulation and which valve when so positioned abuts at its rear end against a supporting structure in order to relieve certain of the fitting parts of the 40 effect of pressure of the medium passing through the fitting.

A further object of the present invention resides in the providing a new and novel form of combined valve-rod shield or cover 45 and operating handle whereby when the shield is in place upon the fitting the valve-rod is protected and completely hidden from view and whereby when such shield is detached may be readily fitted to the valve-rod for operating the same.

Other and further objects of the invention reside in the providing of a new and novel valve attachment for clearing the valve seat of deposits and in the providing of the 55 fitting with a deposit or drip chamber.

Other and still further objects reside in the providing of general details of construction and arrangement of parts as will hereinafter more fully appear.

The invention consists of the improvements hereinafter described and finally claimed.

The nature, characteristic features and scope of the invention will be more fully understood from the following description 65 taken in connection with the accompanying drawings forming part hereof and in which:

Figure 1, is a view in central section of a fitting embodying the invention, Fig. 2, is a view in horizontal section taken upon the 70 line 2—2 of Fig. 1, and Figs. 3, and 4, are views taken upon the lines 3—3, and 4—4, respectively, of Fig. 1.

In the drawings the fitting is of general cruciform configuration, see Fig. 1, and in 75 manufacture is made up of a very small number of parts, five by actual count, thus insuring cheapness of manufacture, simplicity of construction and efficiency in use. As the parts all have screw-threaded relation with one another the fitting may be 80 readily assembled. The part 10, of the fitting, is of angular construction and embraces a horizontal inlet connection 11, a similarly disposed extension 12, an upwardly extended outlet connection 13, and a depending extension 14, constituting a combined expansion and deposit or drip chamber, all of which parts are integral. These 85 extensions and connections are arranged at right angles to one another. The inlet connection 11, has extended thereacross and integral therewith a partition, centrally apertured to provide a valve-seat 15. Fitted to the extension 12, so that its forward end projects well into the vertical bore of the part 10, is a one piece horizontally disposed bushing 16, provided with a hexagonal part 17, terminating in a forwardly extended shoulder 18, and a rearwardly extended screw 100 threaded portion 19. Having screw threaded relation with the bushing 16, so as to be movable endwise therethrough is a valve-stem 20, provided with a valve 21, for cooperative engagement with the valve-seat 15, 105 both for opening and closing the opening therethrough and for cleansing the same of deposits which may be present by means of the drill point 22, projected from the valve 21, which has a nice sliding fit with said 110

opening. The valve is provided with oppositely disposed beveled parts 23, and 24, for a purpose to presently appear.

The outer end of the valve-rod is squared at 25, to receive an operating device hereinafter to be described. The valve-rod is suitably packed as at 26. Having screw threaded relation with the part 19, of the bushing 16, and completely inclosing and hiding entirely from view the valve-rod is a shield or hood 27. The shield abuts against the part 17, of the bushing 16, and the shoulder 18, of the bushing in turn abuts against the extension 12, of the part 10, so that from end to end the valve-rod is completely inclosed. That part of the shield 27, which normally is adjacent the bushing end is provided with a boss 28, having formed therein a squared opening 29, of a size for operatively engaging the squared end 25, of the valve-rod so that the shield may be used as an operating handle when detached from the fitting. The boss 28, has also drilled therein a small opening 30. A lug 33, formed integral with the extension 12, of the part 10, has also drilled therethrough a small opening 32. In practice a wire seal 31, is used for sealing the shield with respect to the part 10, the wire of the seal being passed through the openings 30, and 32, whereby to remove the shield to operate the valve-rod, it is necessary to break the seal. The seal 31, is usually located beneath the fitting as shown. Thus unauthorized persons are not apt to tamper with the fitting and should they do so an authorized agent inspecting the system has knowledge of such act so that a thorough inspection follows. In practice, and speaking now particularly of the use of high pressure gas in residences, business houses and the like, the fitting parts are so constructed that when once set, no adjustments are necessary for efficient operation. In this connection, it may be stated that the relative position of the valve 21, to its valve seat 15, as shown, in the drawings, is proportioned for this result. It will be noted that the bushing 16, is extended outwardly so that the beveled part 23, of the valve will abut against the open end 34, thereof. Thus pressure from gas passing through the fitting to the outlet 13, will not be exerted upon the worm of the valve-rod or upon the valve-rod packing. The beveled part 24, of the valve, when in closed position, forms a snug fit with respect to the opening in the valve seat 15.

What I claim is:

1. A fitting of the class described embracing a casing having a relatively large inlet connection equipped with a valve seat having a contracted opening therethrough, a detachable valve-stem bushing projected into said casing and disposed opposite the valve-seat, an endwise movable valve-stem carrying a valve-piece operative through

said bushing for closing the contracted opening, said valve-piece being adapted to abut against the inner bushing end to maintain a normal working thoroughfare of determined maximum, a detachable shield operatively connected to form a joint to prevent the escape of a medium under pressure and which shield entirely incloses the valve-stem end when the valve is in its full open position and means acting as a seal connected between said casing and said shield. 75

2. A fitting of the class described embracing a casing having relatively large inlet connection equipped with a valve-seat having a contracted opening therethrough, said casing beyond and below said valve-seat being provided with a combined expansion and deposit or drip chamber, a detachable valve stem bushing projected into said casing and disposed opposite the valve-seat, an endwise movable valve-stem carrying a valve-piece operative through said bushing for closing said contracted opening, said valve-piece being adapted to abut against the inner bushing end to maintain a normal working thoroughfare of determined maximum, a detachable shield operatively connected to form a joint to prevent the escape of a medium under pressure, which shield entirely incloses the valve-stem and when said valve is in its full open position and means acting as a seal connected between said casing and said shield. 85 90

3. In a fitting of the class described the combination of a casing provided with an inlet valve thoroughfare, a valve-stem equipped with a valve-piece for controlling the valve thoroughfare, said valve-stem having a squared end, and a shield detachable with respect to the casing and entirely inclosing the exposed end of the valve-stem, said shield having formed in its wall a squared depression capable of engagement over the valve stem end when the shield is detached. 100 105 110

4. In a fitting of the class described the combination of a casing provided with a relatively large inlet connection having a valve seat with a contracted opening therethrough, a valve-stem equipped with a valve piece for closing said contracted opening, a detachable shield operatively connected with respect to the casing to form a joint for preventing the escape of a medium under pressure, which shield entirely incloses the valve-stem end when the valve-piece is in its full open position, and a wire seal connected between said casing and said shield. 115 120

5. A fitting for systems utilizing high pressure embracing a valve-casing of cruciform contour having a central chamber in communication with which are horizontal and vertical extensions, of which one of the horizontal extensions comprises a relatively large inlet having a valve-seat provided 125 130

with a contracted opening therethrough and of which the other of said horizontal extensions is equipped with a valve-stem bushing having a central screw-threaded opening, 5 the flat forward end of which bushing is projected well into said chamber, and an endwise movable screw-threaded valve-stem operative through said bushing provided with a cylindrical valve piece, the opposite 10 ends of which are beveled, of which the outer beveled portion is operative for abutting against the sharp peripheral edge of the bushing opening in open position of the valve and the inner beveled portion is operative 15 for abutting against the sharp peripheral edge of the said contracted opening in the closed position of said valve.

6. A fitting for systems utilizing high pressure embracing a valve casing provided 20 with a relatively large inlet connection having extended thereacross a partition forming a valve-seat provided with a flat face having a contracted opening therethrough, that portion of the valve casing immediately 25 beyond the contracted opening forming a combined separating and deposit chamber, a bushing within the casing provided with a central screw-threaded opening, the flat forward end of which bushing is projected well 30 into said chamber, an endwise movable screw-threaded valve-stem operative through said bushing provided with a cylindrical valve-piece, the opposite ends of which are beveled, of which the outer beveled portion 35 is operative for abutting against the sharp peripheral edge of the bushing opening in open position of the valve and the inner beveled portion is operative for abutting against the sharp peripheral edge of the 40 said contracted opening in the closed position of said valve, and a short drill point carried by the outer end of said valve-piece for entering said contracted opening during the closing of the valve, said drill point being substantially free of the said opening in 45 the open position of the valve.

7. A fitting for systems utilizing high pressure embracing a valve casing of cruciform contour provided with a central chamber and horizontal and vertical extensions, 50 of which one of the horizontal extensions comprises a relatively large inlet connection having extended thereacross a partition forming a valve-seat having a contracted 55 opening therethrough and of which the other of said horizontal extensions is equipped with a bushing projected into said chamber, the vertical extensions forming an outlet connection and a deposit chamber respectively, a valve-stem carrying a valve-piece operative through said bushing for 60 closing said contracted opening, which valve-piece in open position abuts against the projected end of said bushing to close 65 the opening therethrough and a detachable

shield operatively connected with respect to the casing to form a joint to prevent the escape of a medium under pressure passing through the casing, which shield entirely incloses the valve-stem end when the valve is 70 in its full open position.

8. A fitting for systems utilizing high pressure embracing a casing provided with a relatively large inlet having a contracted thoroughfare therethrough, a valve-stem 75 bushing, one end of which is projected an appreciable distance within the casing interior, a valve-stem carrying a valve-piece operative through the bushing for closing said contracted thoroughfare, which valve-piece normally abuts against said projected portion of the bushing to maintain a working thoroughfare of determined maximum, and a detachable shield entirely inclosing the valve-stem end in said normal position 80 of the valve-piece, which shield is operatively disposed to prevent the escape of a medium under pressure.

9. A fitting for systems utilizing high pressure embracing a casing provided with 90 a relatively large inlet, having a contracted thoroughfare therethrough, a valve-stem bushing, one end of which is projected an appreciable distance within the casing interior, a valve-stem carrying a valve-piece 95 operative through the bushing for closing said contracted thoroughfare, which valve-piece normally abuts against said projected portion of the bushing to maintain a working thoroughfare of determined maximum, 100 and a detachable shield entirely inclosing the valve-stem end in said normal position of the valve-stem, which shield is operatively disposed to prevent the escape of a medium under pressure, and means operatively disposed to prevent the unauthorized detachment of said shield.

10. A fitting for systems utilizing high pressure embracing a casing provided with a relatively large inlet having a contracted 110 thoroughfare therethrough, a valve-stem bushing having a central screw-threaded opening therethrough, one end of which bushing projects an appreciable distance within the casing interior, a valve-stem 115 carrying a valve-piece operative through the bushing for closing said contracted thoroughfare, which valve-piece normally abuts against said projected portion of the bushing to maintain a working thoroughfare of determined maximum and by such abutment serves to close the screw-threaded opening of said bushing and a detachable shield entirely inclosing the valve-stem end in said normal position of the 120 valve-piece, which shield is operatively disposed to further prevent escape of a medium under pressure which may leak through said bushing opening as closed by said valve-piece.

11. In a fitting of the class described, the 130

- combination of a casing having an inlet thoroughfare, a valve-stem and its complementary valve-piece for closing said thoroughfare and a shield detachable with respect to the casing for entirely inclosing the exposed end of said valve-stem which shield is shaped and proportioned for valve-stem engagement when detached from the casing.
- 10 12. A fitting for systems utilizing high pressure embracing a casing provided with a relatively large inlet having a contracted thoroughfare therethrough, a valve-stem equipped with a valve-piece for closing said thoroughfare and a detachable shield for entirely inclosing the valve-stem in its full open position, said shield being operatively connected with respect to the casing to prevent leakage of a medium under pressure.
- 15 13. A fitting for systems utilizing high pressure embracing a valve casing of cruciform contour having a central chamber in communication with horizontal and vertical extensions of which one of the horizontal extensions comprises a relatively large inlet

having a valve seat provided with a contracted opening therethrough, and of which the other of said horizontal extensions is equipped with a valve-stem bushing projected into said central chamber and disposed opposite said valve seat, the said vertical extensions forming an outlet connection and a deposit chamber respectively, an endwise movable valve-stem carrying a valve-piece operative through said bushing 35 for closing said contracted opening, which valve-piece being adapted to abut against the inner bushing end to maintain a normal working thoroughfare of determined maximum and a detachable shield operatively 40 connected to form a joint to prevent the escape of a medium under pressure, which shield entirely incloses the valve-stem end when the valve is in its free open position.

In testimony whereof, I have hereunto 45 signed my name.

GEORGE W. SAVAGE.
